US0D1114037S

(12) **United States Design Patent** (10) **Patent No.:** **US D1,114,037 S**
(45) **Date of Patent:** **** Feb. 17, 2026**

(54) **PROJECTOR**

(71) Applicant: **SHENZHEN VANTOP TECHNOLOGY & INNOVATION CO., LTD.**, Shenzhen (CN)

(72) Inventors: **Danni Guo**, Shenzhen (CN); **Yang Cui**, Shenzhen (CN); **Qi Jiang**, Shenzhen (CN); **Ming Wang**, Shenzhen (CN)

(73) Assignee: **SHENZHEN VANTOP TECHNOLOGY & INNOVATION CO., LTD.**, Shenzhen (CN)

(**) Term: **15 Years**

(21) Appl. No.: **29/943,502**

(22) Filed: **May 22, 2024**

(51) LOC (15) Cl. **16-02**

(52) U.S. Cl. **D16/230**

(58) **Field of Classification Search**

USPC D16/221-231, 235; D21/514; D26/93, D26/94, 98, 99, 106, 108

CPC G03B 21/16; G03B 21/145; G03B 21/32; G03B 21/14; G03B 21/00; G03B 21/001; G03B 21/003; G03B 21/12; H04N 9/31; F16M 11/125; G01V 8/14

(57) **CLAIM**

The ornamental design for a projector as shown and described.

DESCRIPTION

FIG. 1 is a perspective view of a projector showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2; and,

FIG. 11 is an enlarged view of portion 11 shown in FIG. 2. The dash-dash broken lines in the drawings depict portions of the projector that form no part of the claimed design. The dot-dash broken lines represent boundaries of the enlarged portions and form no part of the claimed design.

1 Claim, 11 Drawing Sheets
